US00D786718S

(12) **United States Design Patent** (10) **Patent No.:** **US D786,718 S**
(45) **Date of Patent:** **** May 16, 2017**

(54) **LEVEL**

(71) Applicant: **Milwaukee Electric Tool Corporation**,
Brookfield, WI (US)

(72) Inventors: **Joseph William Burge**, Milwaukee, WI
(US); **Adam Christopher Resnick**,
Waukesha, WI (US)

(73) Assignee: **Milwaukee Electric Tool Corporation**,
Brookfield, WI (US)

(**) Term: **15 Years**

(21) Appl. No.: **29/547,846**

(22) Filed: **Dec. 8, 2015**

(51) LOC (10) Cl. **10-04**

(52) U.S. Cl.

USPC **D10/69**

(57) **CLAIM**

We claim the ornamental design for a level, as shown and described.

DESCRIPTION

FIG. 1 is a right side perspective view from above of another embodiment of the claimed design;

FIG. 2 is a right side view of the claimed design of FIG. 1;

FIG. 3 is a left side view of the claimed design of FIG. 1;

FIG. 4 is a top view of the claimed design of FIG. 1;

FIG. 5 is a bottom view of the claimed design of FIG. 1;

FIG. 6 is a rear view of the claimed design of FIG. 1;

FIG. 7 is a front view of the claimed design of FIG. 1;

FIG. 8 is a right side perspective view from below of the claimed design of FIG. 1; and,

FIG. 9 is a rear perspective view from above of the claimed design of FIG. 1.

The ornamental design which is claimed is shown in solid lines in the drawings. The broken lines in the drawings are for illustrative purposes only and form no part of the claimed design.

1 Claim, 9 Drawing Sheets
